UNITED STATES PATENT OFFICE.

WASHINGTON A. ROEBLING, OF BROOKLYN, NEW YORK.

ROPE-DRIVING MACHINERY.

SPECIFICATION forming part of Letters Patent No. 270,129, dated January 2, 1853.

Application filed June 28, 1852. (No model.)

To all whom it may concern:

Be it known that I, WASHINGTON A. ROEBLING, of Brooklyn, in the county of Kings and State of New York, have invented new and useful Improvements in Rope-Driving Machinery for Drawing Vehicles, of which the following is a specification.

My invention is applicable to drawing cars and other vehicles on railways, cable-tramways, and inclines, and also to the propulsion of canal-boats. It consists essentially of a pair of rope-driving drums rotated by a friction-drum interposed between them. In practice I mount the shafts of the rope-driving drums in sliding boxes, so that the surfaces of the said drums will be drawn against the friction-drum by the stress of the rope, and I incline the axes of the drums in such a way that the rope has a straight lead from one drum to the other, both on top and bottom; and on the upper side (or on the opposite side from that which is in the line of draft) it is conducted from one groove of the first drum to the next or succeeding groove of the other drum, the obliquity required to carry the rope from one groove to the next being imparted in passing round the drum, and all tendency of the rope to crowd or climb one coil on another being avoided. The form or shape of the peripheral surfaces of the drums is an important feature. All of the drums may be formed with such slight concavity or bevel on their peripheries as by compensating for their relative obliquity in position to cause them to work in close frictional contact from end to end, or through sufficient extent of their surface. In this case the drums are "hyperboloids" rotating in contact with each other. Again, the peripheral surfaces of the rope-driving drums may be beveled or concaved to a hyperbolic curve, depending upon the angle of inclination of the rope-driving drums, the intermediate or friction drum being made a true cylinder, and its peripheral surface of course straight. The line of contact between the drums will be a straight line. Conversely, the rope-driving drums may be made true cylinders, and the intermediate or friction drum made a hyperboloid, the bevel or concavity of its periphery being such as to insure the line of contact between the drums being a straight line. It will be found in practice that the bevel or concav-

ity of the surface of the friction-drum is so slight that if made a true cylinder perfect contact between it and the rope-driving drums will be obtained in a very short time by the wearing down of the surface through use.

In the accompanying drawings, Figure 1 is a plan view of the combined drum mounted in a suitable frame or housing. Fig. 2 is an end view of the same. Fig. 3 is a diagram, viewed from the front, illustrating the relative inclination of the axes of the drums.

The two rope-driving drums A A' have their axes inclined to each other sufficiently to cause the rope R to be carried in a straight or direct line, with a fair lead from its groove or position on one drum to its proper groove or position on the other drum without the interposition of a guiding-sheave.

The friction-drum B, which is interposed between the rope-driving drums A A' in close contact with their surfaces, has its axis inclined to an angle midway between the relative angle of inclination of the two other drums—that is to say, the axes of the drums A and A' being, as in the present illustration, inclined in each direction from a horizontal position, the axis of the friction-drum B will be horizontal.

In Fig. 3 the axis of the drum A is represented at a, that of the drum A' at a', and that of the drum B at b. In this illustration, where the lower surfaces of the drums are supposed to be in the line of draft, the grooves in the two drums are in line on such lower surfaces, and the drums are tipped or inclined in opposite directions, each one-half the width between the grooves, so that at top the first groove of one drum is opposite the second groove of the other, and so on in succession. The surfaces of each of the drums are beveled or concaved to such an extent that contact is secured between them at all desired points, and so that at every such point of contact the surfaces of the drums in contact will bear a constant unchanging relation and ratio to each other in radius. Hence the contact-points of the respective drums will be moving constantly at the same velocity, except as hereinafter mentioned. The tendency of the two rope-driving drums thus operated will be to move spirally and sidewise in an opposite direction to the friction-drum with which they are in contact. This is prevented by forming several grooves in the faces of the driving

drums, as shown at *g g*, and corresponding tongues or flanges on the friction-drum *B*, as shown at *p*. These tongues and grooves, fitting one into the other, prevent sidewise motion and furnish additional friction, thereby aiding in imparting the required revolution to the rope-driving drums. This provision can manifestly be changed by a transposition of the tongues and grooves, the grooves being made on the friction-drum *B* and the tongues or flanges on the rope-driving drums *A A'*.

In practice I prefer to retain a large proportion of the surfaces of the drums that come in frictional contact with each other free from grooves or flanges, so as to cause the pitch-line to coincide and be identical with the line of the surface.

It will be understood that the flanges and grooves cannot move together with exact harmony or without slip. This constitutes the exception hereinbefore referred to in reference to the avoidance of slip between the contact-surfaces.

The journal-bearings *D D'* of the shafts *S S'* of the rope-driving drums *A A'* are made movable to such an extent as will permit these drums to be drawn strongly against the friction-drum *B* in proportion to the tension of the rope *R*. The power is applied to the drum *B*, and the adhesion or friction produced imparts motion to the rope-driving drums *A A'*.

By my improvement side friction or pressure against the journal-bearings is relieved, and is far less than it would be by the use of pinions

or other expedients heretofore used for such purpose.

Having thus described my invention, what I claim as new therein, and desire to secure by Letters Patent, is—

1. The combination of a pair of rope-driving drums on axes oblique to each other, and a friction-drum interposed between them for imparting motion thereto, substantially as described.

2. The combination of a pair of rope-driving drums, with axes oblique to each other, and an interposed friction-drum, said drums being formed with concave or beveled faces, substantially as and for the purposes herein set forth.

3. The combination of a pair of rope-driving drums running on axes oblique to each other in movable boxes or bearings, and an interposed friction-drum for imparting motion to said rope-driving drums, substantially as described.

4. The combination of a pair of rope-driving drums mounted on axes oblique to each other, and an interposed friction-drum for imparting motion to the same, with tongues or flanges *p* and grooves *c* in the respective drums for the purpose of increasing friction between the drums and of preventing lateral movement, as set forth.

WASHINGTON A. ROEBLING.
